UNITED STATES PATENT OFFICE.

JOHN C. KASHMERE AND JAMES K. ROBERTS, OF WILKES-BARRE, PENNSYLVANIA,
ASSIGNORS TO WALTER C. WILLIAMS, OF WILKES-BARRE, PENNSYLVANIA.

TOY VEHICLE.

Application filed February 23, 1922. Serial No. 538,685.

To all whom it may concern:

Be it known that we, JOHN C. KASHMERE and JAMES K. ROBERTS, citizens of the United States, residing at Wilkes-Barre, in the county of Luzerne and State of Pennsylvania, have invented new and useful Improvements in Toy Vehicles, of which the following is a specification.

This invention relates to child's foot-propelled toy vehicles, the primary object of the invention being to generally simplify and improve the construction and operation of such devices, as well as to enhance the efficiency of the same.

A further object of the invention is to provide a toy vehicle of that type wherein the child seats itself upon the vehicle and propels the same by applying the feet to the ground, and wherein the danger of breakage or derangement of the various parts of the vehicle is reduced to the minimum, and wherein its operation is smooth and regular.

A further object of the invention is to provide a toy of the character stated which is adaptable to children of various sizes, that is, the platform and steering mechanism may be elevated or lowered as desired to accommodate itself to the size of the child, improved locking means being employed for holding these adjustable parts rigidly in the required positions.

With these and other objects in view, the invention consists of the features of construction, combination and arrangement of parts, hereinafter fully described and claimed, reference being had to the accompanying drawing, in which:

Figure 1 is a longitudinal sectional view taken through a toy vehicle constructed in accordance with the invention;

Figure 2 is a fragmentary horizontal plan view of the rear portion of the vehicle, and

Figure 3 is a vertical sectional view taken through the front wheels of the vehicle and the steering post thereof.

Referring now more particularly to the drawing, the supporting frame of the vehicle is indicated at 4. The frame is, in the present instance, formed of metal tubing of comparatively small diameter, so as to be of light weight and yet possess sufficient strength to withstand the strains to which the vehicle will be subjected. Near the rear end of the tube constituting the greater por-

tion of the frame 4 there is secured a T-union 5, the rear end of the union having secured therein the forward end of a section 6 constituting a part of frame 4, while a hollow sleeve 7 is secured in the upstanding portion of the union 5. The rear end of pipe section 6 is connected with a T-joint or union 8, the latter being disposed laterally of frame 4, and receives at its ends axle casings 9.

The rear axle for the vehicle is indicated generally at 10 and is rotatably mounted within union 8 and axle casings 9, protruding at its ends beyond the extremities of said axle casings and having wheels 11 of suitable size rotatably mounted thereon. A washer 12 is interposed between the inner face of each wheel and the edge of the adjacent tubular section 9, to minimize friction as will be understood. The axle 10 extends entirely through wheels 11, and its ends are upset or mushroomed as at 13 to maintain the wheels permanently attached to the axle ends. Washers 14 may be interposed between the overturned ends of the axle and the adjacent wheel surfaces.

The sleeve 7 extending upwardly from union 5 snugly receives a standard 15, the latter being secured at its upper end to a seat or platform indicated at 16. The standard 15 is relatively long and protrudes through an opening in the lower portion of T-union 5, as shown in Figure 1.

This standard 15 is adjustable longitudinally in the sleeve 7, and is to be maintained rigidly in any of its many positions of adjustment. To facilitate this adjustment and to rigidly hold the standard in adjusted positions, the sleeve 7 upon one side is slit inwardly from its upper edge as at 17, and the upper end of the sleeve is reinforced or enlarged as at 18 and is provided with outwardly extending spaced parallel ears 19, one attached to the sleeve upon each side of the slit 17, and connected by a bolt 20. From this construction it is obvious that adjustment of standard 15 within the sleeve 7 may be readily made by simply loosening the nut upon bolt 20, and when the desired adjustment has been made the said standard and sleeve may be rigidly held together by tightening the nut upon the said bolt 20.

The longitudinal frame member 4 is bent or inclined upwardly near its forward end, and carries at its forward end a T-union 21.

The body of this union member has its open ends disposed vertically and receives a hollow steering post 22. This steering post is inserted from the lower end of the said union and is rotatably mounted in the latter. The lower extremity of the steering post is rigidly connected with the upstanding portion of a horizontally disposed T union 23, and a sleeve 24 is interposed between the said upstanding portion of union 23 and the lower edge of union 21. The laterally disposed arms of union 23 constitute a housing for front axle 25 of the vehicle, and the extremities of this axle rotatably carry the forward or steering wheels 26 of the vehicle; the said wheels being affixed to the axle ends in the same manner as are the rear wheels 11 of the vehicle to the rear axle.

20 The hollow steering post 22 snugly receives the standard or guide post 27, the latter being adjustable within the said post. The steering post 22 protrudes a slight distance above the upper end of union 21, and this protruding end is enclosed by a collar 28. This collar is provided with an aperture adapted to aline with a similar aperture in the underlying steering post 22, the said apertures threadedly receiving the shank of a set screw 29. The inner extremity of this threaded shank of screw 29 engages the guide post or standard 27 and maintains steering post 22 and sleeve 28 rigidly with the said standard. The upper extremity of the standard is provided with handle bars indicated at 30 to be gripped by the hands of the child to steer the vehicle.

25 The several parts of the vehicle may be constructed of any suitable material. In the present instance, for the purpose of illustration only, the frame 4 is constructed of light rigid metal, as is sleeve 7 and the steering post. The axle and its housing are of suitable metal, while the axle for the steering wheels and its housing and supporting elements are also of proper metallic construction. The platform or seat 16 and the handle bars 30 are constructed of wood, while the wheels 11 and 26 may be either 30 of wood or metal. The several parts connecting with the various unions which are employed may be threaded, brazed or pinned thereto, it being essential only that they be rigidly connected with their various connecting parts.

35 In operating the device, it will be understood that the child seats itself upon platform 16 and grasps the handle bars 30. The steering wheels may be readily turned by manipulating the handle bars, and the vehicle is propelled by the child pushing upon the ground with its feet. When it is desired to change the distance of the seat and handle bars from the ground, it is but necessary to loosen the nut upon bolt 20 and

set screw 29, whereupon the proper adjustments of the standards 15 and 27 may be made. When this has been done the bolt and set screw may be tightened to rigidly hold the parts in their new adjusted position.

40 By constructing the device in the manner specified, it is apparent that there has been provided a child's self-propelled vehicle presenting a rigid structure capable of withstanding the strains to which it will necessarily be subjected in use, which can not become readily broken or disordered, which will operate efficiently, and which will not be of such weight as to preclude its use by children of tender age.

45 In vehicles of a like nature heretofore proposed, and to a great extent used, the rear wheels have been mounted upon wooden pintles, and the steering post, constructed of wood, passes through the forward end of the wooden platform of the vehicle. A very common objection to such device is that should the vehicle become wet the pintles will swell, as will the steering post 50 of the vehicle, in many instances precluding further use of the vehicle until repairs of a more or less elaborate nature have been made. By constructing the device in the manner above specified, these objections are 55 wholly overcome, as the presence of moisture upon the various movable parts will not impair the operation thereof.

60 While the above is a description of the invention in its preferred embodiment, it will be understood that various changes in the construction and arrangement of parts may be resorted to without departing from the spirit of the invention as defined by the claims.

65 Having thus fully described our invention, we claim:—

1. In a toy vehicle, a frame including a longitudinal bar, an axle carried at the rear end of the bar, rear wheels carried by said axle, a T-union at the forward end of the bar, a steering post rotatably mounted in said T-union, a second T-union at the lower end of said steering post, a front axle journaled in said second T-union, front wheels carried by said front axle, and handle bars carried by said steering post.

2. In a toy vehicle, a frame including a longitudinal bar, an axle carried at the rear end of the bar, rear wheels carried by said axle, a steering post rotatably mounted at the forward end of the bar, a T-union at the lower end of said steering post, a front axle journaled in said T-union, front wheels carried by said front axle, and handle bars carried by said steering post.

3. In a toy vehicle, a frame including a longitudinal bar, an axle carried at the rear end of the bar, rear wheels carried by said axle, a steering post rotatably mounted at

the forward end of the bar, a T-union having an upstanding branch fixed to said steering post and having horizontally disposed branches forming a bearing sleeve, an axle 5 journaled in said bearing sleeve, front wheels carried by said axle, and means connected with said steering post for rotating the same.

4. In a toy vehicle, a frame, a sleeve at 10 the forward end of said frame disposed vertically, a steering post rotatable in said sleeve, a standard slideable in said steering post, a set collar enclosing said standard, the said collar and standard having registering apertures, a set screw threaded in 15 said apertures, and wheels carried by the lower end of said steering post.

5. In a toy vehicle, a supporting frame, a T-union at the forward end of said frame 20 having its opposite ends disposed vertically, a hollow steering post rotatably supported in said T-union, one end of said post protruding beyond the upper end of said union, a sleeve enclosing said protruding end, the 25 said sleeve and steering post having threaded apertures, a T-union rigidly secured to the lower end of said steering post, an axle passing through said union, wheels carried by said axis, a spacing collar interposed between the said T-unions, a 30 standard received within said steering post, and a set screw engageable in the said threaded registering openings.

6. In a toy vehicle, a frame, a T-union 35 near the rear end of said frame having an opening extending upwardly, a sleeve secured at its lower end in said opening, the said sleeve being split inwardly from its

upper end, ears upon the upper extremity of said sleeve one on each side of said split 40 portion, a bolt connecting said ears, and a seat carrying standard snugly engaged in said sleeve.

7. In a toy vehicle, a frame including a longitudinal bar, an axle carried at the rear end of the bar, rear wheels carried by 45 said axle, a steering post rotatably mounted at the forward end of the bar, a T-union having an upstanding branch fixed to said steering post and having horizontally disposed branches forming a bearing sleeve, an axle journaled in said bearing sleeve, front wheels carried by said axle, a standard slideable in said steering post, fastening 50 means for fixing said standard to the steering post, and handle bars carried by the standard.

8. In a toy vehicle, a longitudinal frame member including divided sections, a T-union having lateral branches and an up-standard branch, said lateral branches receiving and coupling adjacent ends of said divided sections of the longitudinal frame member, and said union having an opening 60 in the bottom thereof, a sleeve secured in the upstanding portion of said union, said sleeve being split at its upper end, a standard slideable in said sleeve and in the opening in the bottom of the union, means for drawing the split portion of the sleeve together to clamp the standard, and a seat 65 supported by the standard.

In testimony whereof they affix their signatures.

JOHN C. KASHMERE.
JAMES K. ROBERTS.
